THREAD CONTROL MEANS

Albert S. Riviere, deceased, late of Chicago, Ill.,
by John F. Cahill, administrator de bonis non,
assignor to Union Special Machine Company,
Chicago, Ill., a corporation of Illinois

Application July 30, 1940, Serial No. 348,373

22 Claims.

(Cl. 112—242)

This invention relates to thread control means useful with textile machinery, including sewing machines of various types which produce single seams, independent parallel seams, or over-edge seams from two or more threads.

The aim of this invention is to insure uniform release of a plurality of yarns at a predetermined rate or rates and thereby attain, for example in the case of sewing machines of the kind referred to, regularity both with regard to the size and the tightness of the stitching produced in such machines, and at the same time make it possible to vary the character of the seams. This advantage is realized, as hereinafter more fully disclosed, in a thread control means including a freely revolving wheel which provides annular surfaces with which individual threads engage in peripheral controlling contact en route from separate sources of supply to the respective instrumentalities of the machine by which they are manipulated, the circle diameters of the annular surfaces being such that during each rotation of the wheel, corresponding proportional lengths of the threads are tolled off; and associate regulatable means whereby the several threads may be maintained either under uniform tension of a definite degree, or under different tensions—all in accordance with the characteristics desired in the work produced by the machine.

A further object of this invention is to secure the foregoing advantages in a thread control device which is simple, inexpensive and readily attached to existing machines without entailing any changes whatever, either in their construction or in their normal mode of operation.

Other objects and attendant advantages will appear from the following detailed description of the aforementioned drawings, wherein Fig. I is a perspective view of an over-seaming sewing machine conveniently embodying the improved thread controlling means.

Fig. II is a fragmentary view in plan of the various thread control means drawn to a larger scale.

Fig. III is a front view of the thread control means.

Fig. IV is a cross-sectional view taken as indicated by the angled arrows IV—IV in Fig. III.

Fig. V is a fragmentary view in side elevation of a two-thread cup feed sewing machine incorporating the thread control means in accordance with this invention.

Fig. VI shows the edge view of the thread measuring wheel included in the thread control means featured in Fig. V.

Fig. VII is a view similar to Fig. V showing this invention in connection with a three-thread cup feed sewing machine.

Fig. VIII shows the edge view of the thread measuring wheel featured in Fig. VII; and

Fig. IX is a view corresponding to Fig. IV showing a modification of my invention.

Referring first more particularly to Fig. I, the sewing machine there delineated is of a well-known type of the construction shown and described in U. S. Patent No. 1,751,508, granted to Norman V. Christensen on March 25, 1930, having a base 1 with a standard 2 rising therefrom and affording guidance for an endwise reciprocating needle bar 3 which is inclined somewhat to the vertical. Forming a part of the base 1 is a work support 4 which is appropriately apertured for passage of the needle 5 on the bar 3; and cooperating with the needle below the work support is a lower looper 6 with which in turn cooperates an auxiliary or over-edge looper 7. By the combined action of these three instrumentalities, a seam is formed around the edge of the fabric F in a well-known way as the latter is progressed on the work support 4 by a feed dog, not shown. Journalled at one end in a pedestal bearing 8 upstanding from the extended lower portion 9 of the machine base; and journalled at the other end in the rear wall of the standard 2 is a rock shaft 10 which carries a thread take-up 11. The needle bar 3, the loopers 6 and 7, and the take-up 11 are all operated by mechanism concealed within the machine frame, which mechanism is driven by power applied to a drive wheel shown at 12.

The thread control means with which the present invention is more especially concerned, includes, as exemplified in Figs. I—IV, a wheel 15 having circumferential grooves 16, 17 and 18 with the annular bottom surfaces of which, the threads N, L and L' contact en route from their respective sources of supply (not shown) to the needle 5, the main looper 6 and the over-edge looper 7. The threads may be passed only part way around the wheel, but in order to insure more positive controlling contact, they are preferably wrapped one or more times around the respective grooves. The groove 16 for the needle thread N is, in the present exemplification of 45 small diameter as compared to that of the grooves 17 and 18 for the looper threads L and L', which latter grooves are shown as being of equal diameters. The wheel 15 is mounted to revolve freely about a screw stud 19 engaged in a bracket 50 20 (Figs. II and III) which is detachably secured, by suitable means not illustrated, to the right hand side wall of the standard 2 as viewed in Fig. I. Extending from the bracket 20 adjacent the wheel 15 is another stud 21 whereon 55 are mounted pairs 22, 23 and 24 of freely revolvable tension disks, which pairs are respectively aligned with the grooves 16, 17 and 18 of said wheel. A helical spring 25 surrounding the projecting end of the stud 21, serves to maintain 60 the disks 22—24 under compression, the pres-

sure being regulatable by means of a thumb nut shown at 26 in engagement with screw threads at the outer end of the stud 21. Interposed in the interval between the wheel 15 and the tensions 22-24 is a finger 27 having eyes 28, 29 and 30, (Fig. II) for respectively directing the threads N, L and L' to the grooves 16, 17 and 18 of said wheel. The finger 27 constitutes an angularly configured guide member 31, whereof the other arm 32 has its end laterally bent as at 33. Upon leaving the wheel 15, the threads N, L and L' pass through eyes 34, 35 and 36 in the end 33 of the guide member 31, which, as shown in Fig. II, is adjustable about the stud 19 and clampable in adjusted positions against the front of the bracket 20 by a jam nut 37 on the inner threaded portion of said stud, see Fig. IV. En route to the needle 5, the thread N, after leaving the eye 34 in the guide 31 passes first through a fixed guide 38 on the machine frame, then through a slotted guide 39 carried by the needle bar 3, then through another fixed guide 40, and finally downward from the last mentioned guide to the eye of the needle as is clearly shown in Fig. I. The looper threads L, L' on the other hand after leaving the eyes 35 and 36 pass through the eyes of fixed guides 41 and 42 on the right hand side of the machine frame, then through eyes 43, 44 in a guide 45 adjustably secured by a screw 46 to the front wall of the machine frame 1, then through the eyes in the arm 47 of the take-up 11, then other eyes 48 and 49 of the adjustable guide 45, then through the eyes of another fixed guide 50 and finally to the eyes of the respective loopers 6 and 7.

As they approach the tension disks 22, 23 and 24, the threads N, L and L' are directed in properly spaced relation by a guide 51, which together with an extension piece 52 is secured to the bracket 20 by the stud 21 whereon the tension disks 22-24 are mounted. On its way from its supply source, the needle thread N passes initially between the disks 53 of an auxiliary tension device 54 carried by the extension piece 52 as shown in Figs. II and III.

With the illustrated arrangement of the threads, it is evident that the wheel 15 will be driven through pull on the thread being consumed at a particular stage in the stitch forming cycle. This action will be readily understood from Fig. I in which the needle 5 is about to descend from its elevated position and consume some of the needle thread N. When this occurs, the measuring wheel 15 will be positively rotated, and, as a result, definite lengths of the looper threads L and L' will be concurrently measured off, the amounts apportioned being determined by the differential ratio as ratio between the circumferences of the grooves 16 and 17, 18. Later on in the stitch forming cycle when the needle N has finished its stroke, and the loopers 6 and 7 begin to advance successively, the wheel 15 will then be rotated by the particular looper thread which at the moment is being consumed, with attendant metering of proportional lengths of the needle thread N in a similar manner. With the set up shown in Fig. I, the above described action results in the formation of stitches of the type No. 504 according to the U. S. standards. A stitch of type 505 may be produced simply by shifting the needle thread N to one of the large diameter grooves of the wheel 15, and the main looper thread L to the small diameter groove of said wheel. In either case, due to the exact proportioning of the measured threads, the stitches will

be absolutely uniform both as regards appearance and set. Obviously, other proportioning of the threads may be had as desired or required for special types of seams, simply by substituting for the wheel 15, other wheels having thread grooves of correspondingly different diameters.

The "cup feed" sewing machine illustrated in Fig. V is generally of the type disclosed in U. S. Patent No. 2,254,875, granted to Charles F. Rubel on September 2, 1941, having an upright frame 55 with a laterally extending portion 56 at its top from which the peripherally contacting feed cups 57 and 58 are suspended by their shafts 59 and 60. By suitable mechanism within the frame 55 the feed cups 57 and 58 are intermittently rotated to advance the work past the stitch forming instrumentalities. Like the feed cups 57 and 58, these stitch forming instrumentalities are actuated by mechanism within the frame, and include an endwise reciprocating needle 61 which passes substantially at right angles through the point of tangency of the wheels, a thread carrying looper 62, and a non-thread carrying over-edge looper or spreader 63. The manner of cooperation of the elements 61-63 in forming the seam stitches from the two threads N and L is exactly as set forth in the application supra and need not therefore be described herein. The thread controlling means of this invention shown with the machine of Fig. V includes a wheel 65 which has but two circumferential grooves 66 and 67 respectively for the threads N and L which grooves are of exactly the same diameter, said wheel rotating freely about a screw stud 68 which engages directly into the rear side of the machine frame. Associated with the wheel 65 is a tension device 69 with paired disks 70 between which the threads respectively run on their way to the wheel, said disks being free to rotate on another stud 71 which engages into the machine frame, and subject to the influence of a compression spring, not shown. After leaving the wheel 65, the needle thread N is first directed through a fixed eye 72, then through an eye 73 on the endwise reciprocating and oscillating shaft 74 of the looper 62, then through eyes 75 and 76 on the bar 77 which carries the needle 61 and finally to the eye of the needle; while the looper thread extends directly to the eye of the looper. Since in Fig. V, the two grooves 66 and 67 of the wheel 65 are of the same diameter, it follows that the amount of thread provided, for the looper 62 will be exactly the same as that provided for the needle 61.

The machine of Fig. VII is exactly like the one last described except in that an auxiliary looper 63a is substituted for the spreader 63 of Fig. V, for manipulating another thread O incident to formation of a three thread over-edge seam in a manner which is also fully explained in the copending application to which reference has been made above. The wheel 65a of the control means shown in Fig. VII has three grooves 66a, 67a and 80 (see Fig. VIII) of equal diameter respectively for the needle thread N, the main looper thread L and the auxiliary looper thread O, so that equal lengths of these threads are measured off during each rotation of the wheel. The tension device 69a associated with the wheel 65a may be exactly like that shown in Fig. V except for having an extra pair of tension disks for the additional thread. In Fig. VII, the main looper thread L, after leaving the wheel 65a passes through a fixed guide eye 81 on its way to the main looper 62a. The auxiliary looper yarn O

likewise passes first through a fixed eye 82 and then, with the needle yarn N, through the eye 73a on the shaft 74a of the main looper 62a on its way from the measuring wheel 65a to the auxiliary looper 63a.

The thread wheels shown in Figs. V, VI, VII and VIII may of course, within the scope of this invention, be modified as described in connection with Figs. I—IV depending upon the effect desired in the seam produced. Furthermore, an additional regulatable tension may be utilized as in Figs. I—IV for any one of the threads in connection with the thread control means shown in Figs. V and VII if this should be found necessary or desirable.

In the modification illustrated in Fig. IX, the grooves 16, 17 and 18 are provided by separate wheel sections 83, 84 and 85 which are detachably secured together by means of a plurality of circumferentially arranged screw bolts 86. The wheel sections are held in positive axial alignment through engagement of hub bosses 87 and 88 on the wheels 83 and 84 into axial recesses 89 and 90 respectively in the wheels 84 and 85. This modified construction is advantageous in that it permits ready interchange of wheels of different sizes for adaptation of this invention to different requirements of practice, and may, if found desirable, be embodied in the thread control wheels 65 and 65a as shown in Figs. V and VII.

The said Albert S. Riviere claimed as his invention, and desired to secure by Letters Patent of the United States:

1. Thread control means for textile machines with plural cooperative thread carrying stitch-forming instrumentalities, including a rotating wheel around which several threads are caused to travel one or more times en route to the individual stitch forming instrumentalities, said wheel being driven by pull on one of the threads incident to consumption of such thread during stitch formation, and having portions of different diameters for the respective threads to effect delivery of said threads at different rates.

2. Thread control means for textile machines with plural cooperative thread carrying stitch-forming instrumentalities, including a rotating wheel around which several threads are caused to travel one or more times en route to the individual stitch forming instrumentalities, and means adjacent the wheel for maintaining the threads under definite tension comprising pairs of coaxially-mounted freely rotatable spring-pressed disks between which the individual threads are respectively passed.

3. Thread control means for textile machines with plural cooperative thread carrying stitch-forming instrumentalities, including a rotating wheel around which several threads are caused to travel one or more times en route to the individual stitch forming instrumentalities, said wheel having laterally-spaced circumferential grooves for the individual threads to keep them definitely separated as they pass around the wheel, and means for maintaining the threads under tension comprising pairs of freely rotatable spring pressed disks mounted on a common stem adjacent the wheel and spaced to correspond with the wheel grooves, between which disk pairs the individual threads are respectively passed.

4. The combination with a sewing machine having a needle and a cooperating thread carrying looper, of means for controlling the needle and looper threads including a rotating wheel

around which the two threads travel one or more times en route to said needle and looper.

5. The combination with a sewing machine having a needle and a cooperating thread carrying looper, of means for controlling the needle and looper threads including a rotating wheel around which the two threads travel one or more times en route to said needle and looper, said wheel having portions of different diameters for the different threads to determine delivery of the threads at correspondingly different rates.

6. The combination with a sewing machine having a needle and a cooperating thread carrying looper, of means for controlling the needle and looper threads including a rotating wheel around which the two threads travel one or more times en route to said needle and looper, and means adjacent the wheel for maintaining the threads under tension.

10 15 7. The combination with a sewing machine having a needle and a cooperating thread carrying looper, of means for controlling the needle and looper threads including a rotating wheel around which the two threads travel one or more times en route to said needle and looper, and means adjacent the wheel for maintaining the threads under tension.

20 25 8. The combination with an over edge sewing machine having a needle, a main thread-carrying looper and an auxiliary thread-carrying looper, of thread control means including a rotating wheel around which the several threads pass en route respectively to the needle, looper and auxiliary looper.

30 35 9. The combination with an over edge sewing machine having a needle, a main thread-carrying looper and an auxiliary thread-carrying looper, of thread control means including a rotating wheel around which the several threads pass en route respectively to the needle, looper and auxiliary looper, and means adjacent the wheel for maintaining the several threads under definite tension.

40 45 10. The combination with an over edge sewing machine having a needle, a main thread-carrying looper and an auxiliary thread-carrying looper, of thread control means including a rotating wheel around which the several threads pass en route respectively to the needle, looper and auxiliary looper, means adjacent the wheel for applying uniform tension to the several threads, and auxiliary tensioning means adjacent the first tensioning means for applying additional tension to one of the threads.

50 55 11. Thread control mechanism for textile machines in which plural manipulating instrumentalities cooperate to incorporate a plurality of individual threads into a single stitch structure, said mechanism comprising annular surfaces with which the respective individual threads have peripheral contact en route to the corresponding manipulating instrumentalities; and means actuated through pull occasioned incident to consumption of one of the threads for compelling concurrent rotation of said surfaces whereby lengths of the remaining individual threads are metered for use by their respective manipulating instrumentalities in proportion to the peripheral speed of the respective annular surfaces.

60 65 12. Thread control mechanism for textile machines in which plural manipulating instrumentalities cooperate to concatenate as many individual threads, said mechanism comprising annular surfaces with which the respective individual threads have peripheral contact en route

70 75

to the corresponding manipulating instrumentalities; means actuated through pull occasioned incident to consumption of one of the threads for compelling concurrent rotation of said surfaces whereby lengths of the remaining individual threads are metered for use by their respective manipulating instrumentalities in proportion to the peripheral speed of the respective annular surfaces; and means for tensioning the threads en route to said surfaces.

13. Thread control mechanism for textile machines in which plural cooperative manipulating instrumentalities cooperate to concatenate as many individual threads, said mechanism comprising a wheel around different portions of which the individual threads are respectively wound en route to the corresponding manipulating instrumentalities whereby, through pull occasioned incident to consumption of one of the threads, the wheel is rotated and lengths of the remaining individual threads are metered for use by their respective manipulating instrumentalities in proportion to the peripheral speed of the portions of the wheel contacted by them; and means for individually tensioning the several threads.

14. Thread control mechanism for textile machines in which plural cooperative manipulating instrumentalities cooperate to concatenate as many individual threads, said mechanism comprising a wheel around different portions of which the individual threads are respectively wound en route to the corresponding manipulating instrumentalities whereby, through pull occasioned incident to consumption of one of the threads, the wheel is rotated and lengths of the remaining individual threads are metered for use by their respective manipulating instrumentalities in proportion to the peripheral speed of the portions of the wheel contacted by them; and means for maintaining the threads in definitely spaced relation as they pass around the wheel.

15. The invention according to claim 13 in which the wheel has spaced ridges to maintain the threads in definite separation.

16. The invention according to claim 13, in which the tensioning means is located adjacent the wheel; and further including a bracket for supporting said wheel and said tensioning means on the machine.

17. Thread control mechanism for textile machines in which plural cooperative manipulating instrumentalities cooperate to concatenate as many individual threads, said mechanism comprising a wheel around different portions of which the individual threads are respectively wound en route to the corresponding manipulating instrumentalities whereby, through pull occasioned incident to consumption of one of the threads, the wheel is rotated and lengths of the remaining individual threads are metered for use by their respective manipulating instrumentalities in proportion to the peripheral speed of the portions of the wheel contacted by them; and means adjacent the wheel and common to the several threads for maintaining the latter under tension.

18. Thread control mechanism for textile machines in which plural cooperative manipulating instrumentalities cooperate to concatenate as many individual threads, said mechanism comprising a wheel around different portions of which the individual threads are respectively wound en route to the corresponding manipulating

instrumentalities whereby, through pull occasioned incident to consumption of one of the threads, the wheel is rotated and lengths of the remaining individual threads are metered for use by their respective manipulating instrumentalities in proportion to the peripheral speed of the portions of the wheel contacted by them; means for maintaining certain of the threads uniformly tensioned; and means for maintaining another thread at a different tension.

19. Thread control mechanism for textile machines in which plural cooperative manipulating instrumentalities cooperate to concatenate as many individual threads, said mechanism comprising a wheel around different portions of which the individual threads are respectively wound en route to the corresponding manipulating instrumentalities whereby, through pull occasioned incident to consumption of one of the threads, the wheel is rotated and lengths of the remaining individual threads are metered for use by their respective manipulating instrumentalities in proportion to the peripheral speed of the portions of the wheel contacted by them; means for applying uniform tension to all of the threads; and auxiliary means for applying additional tension to certain of said threads.

20. Thread control means for determining proportionate rates at which plural threads are fed individually to as many different but cooperative thread-concatenating elements of a textile machine, said means comprising a separate tension for each thread and a wheel having plural peripheral thread engaging portions of different diameters with each of which one of a plurality of the threads is frictionally engaged, said wheel being arranged for rotation by the movement of one of said threads incident to the consumption thereof by one of said thread concatenating elements, and by said rotation adapted to simultaneously supply another thread to an element cooperating with said first named element in the proportion determined by the diameters of the portions of said wheel which are frictionally engaged by said threads.

21. Thread control means for governing the rate at which separate threads are concurrently fed to complementary cooperative stitch-forming devices of textile machines, comprising a separate tension device for each thread; and a wheel formed of interchangeable detachable sections around the perimetric surfaces of which the respective threads are wound, said wheel being rotated through pull occasioned by consumption of one of the threads, so that the rate of advance of the remaining threads is determined and proportioned in accordance with the diameters of the wheel sections about which such remaining threads are respectively wound.

22. Thread control means for textile machines with plural cooperative thread carrying stitch-forming instrumentalities, including a rotating wheel formed of interchangeable detachable perimetrically-grooved sections around which the individual threads are passed one or more times en route to the individual stitch-forming instrumentalities, said wheel being driven by pull on one of the threads incident to consumption of such thread during stitch formation.

JOHN F. CAHILL,
Administrator de bonis non of the Estate of Albert S. Riviere, Deceased.
